ROBERT A. LINCOLN, OF WICHITA FALLS, TEXAS

SLIP JOINT FOR DRILL STEMS

Application filed March 9, 1929. Serial No. 345,683.

My invention relates to a device to be placed in drill stem employed in well drilling which will enable the driller to place a continuous and equal weight upon the drill 5 during the drilling operation.

In deep well drilling for oil, gas, sulphur, and the like, the drill is found to run smoother and more effectively if an equal and steady weight is allowed to rest upon the drill. This 10 weight should not be too heavy but it should be sufficient to exert a thrust upon the bit sufficient to force it into the formation which is being drilled. The difficulty is to keep the weight uniform and to prevent the weight 15 from becoming excessive. The total weight of the drill stem above a drill bit is sometimes far greater than the bit is enabled to support.

It is an object of my invention to provide 20 a slip joint in the drill stem which will enable the driller to suspend the upper portion of the drill stem from the derrick platform and to allow only the lower portion of the drill stem to rest upon the bit so that 25 the weight of the pipe supported by the drill stem can be accurately determined and adjusted.

It is a further object in devices of this 30 kind to provide a slip joint which may be adjusted to prevent relative sliding movement of the two parts of the drill stem while the drill is being inserted into the well but which is capable of release when the drill stem is rotated with the drill upon the bottom 35 of the hole.

It is a further object to provide effective means to prevent the upper and lower sections of the drill stem from becoming connected again during the drilling operations. 40

The invention lies largely in the particular construction and arrangement of the parts making up the improved tool and reference is made to the drawings herewith wherein a preferred embodiment thereof is 45 disclosed.

In the drawings, Fig. 1 illustrates a central longitudinal section through the joint forming the subject matter of my invention.

50 Fig. 2 is a transverse section, somewhat

enlarged, taken on the plane 2-2 of Fig. 1.

The invention provides two relatively 55 telescoping parts. The upper section 1 is a nipple or barrel, the upper end of which is threaded at 2 for engagement with a collar or tool joint 3, which in turn is connected with the joint at the lower end of the upper section of the drill stem. The barrel 1 is of any length but ordinarily a section of about 20 or 22 feet in length is preferred as this allows the telescoping of the joint for a full section of drill stem. The lower end of the barrel is threaded for connection at 4 with a special coupling 5.

The coupling 5 is secured to the lower end 60 of the barrel and its inner diameter is decreased to form a shoulder 6 above which it is threaded at 7 for engagement with the head 8 on the drive stem 9. The lower end of the nipple 5 is threaded at 10 to receive the bushing 11.

The bushing 11 is provided with a threaded 65 portion 12 to engage within the threaded seat 10 of the nipple 5 and above the threaded portion the diameter is decreased and formed into an upwardly extending sleeve 13 to telescope within the nipple 5. The lower end of the bushing 11 has a head 14 thereon for engagement with a wrench or other tool by means of which it may be unscrewed from the nipple 5.

The drive stem 9 is formed to fit within the bushing 11 and has a plurality of radially extending keys or splines 15 to fit within corresponding keyways 16 in the bushing 11. 70 This will be noted from Fig. 2. I have shown four splines upon the drive stem 9 engaging within the bushing, but any desired number may be used. This engagement between the stem and the bushing allows a telescopic movement between the parts, but prevents relative rotation. The lower end of the drive stem is formed with a tool joint pin 17 thereon to engage within the lower section of drill stem, but it is to be understood that any type of coupling between the stem and the tool joint below may be employed.

The upper end of the drive stem 9 is threaded to engage within the head 8, which 75 is adapted to be screwed thereon, said head 100

being threaded externally at its lower end for engagement at 7 with the nipple 5. Above, the head 8, I provide packing means to form a fluid tight contact with the interior of the barrel 1. This packing device is shown as being made up of an upper cup 18, which is directed upwardly to prevent the passage of fluid downwardly past the packing. This packing ring is separated from a second lower packing ring 19 by a spacer 20. The lower packing ring is directed downwardly as will be noted from the drawings. Above and below the two packing rings thus mounted are washers 21 and the entire packing assembly thus constructed is held in place by a lock nut 22 threaded upon the upper end of the drive stem. It will be noted that the head 8, together with the packing members, comprise a sort of piston slidably within the barrel 1 when the head 8 is disengaged from the nipple 5.

It is to be understood that the drive stem 9 is of the same or slightly greater length than is the barrel 1 so that the head 8 may 25 slide upwardly in the barrel for approximately the full length of said barrel. The interior of the drive stem 9 is formed with a water passage 23 so that fluid may pass downwardly through the joint during the operation of the drill.

When the device is to be introduced into the well, the lower section of the drill stem is connected to the joint 17, the drill being at the lower end of the drill stem. The bushing 35 11 and the head 8 are threaded into the nipple 5, approximately as shown in Fig. 1, and the upper section of the drill stem is connected with the barrel 1, as previously noted. As the device is introduced into the well it 40 will be possible to force the drill downwardly to the bottom of the well without telescoping the joint between the drive stem 9 and the barrel 1. If obstacles are encountered during the introduction of the drill into the well 45 the fluid circulation through the drill will be sufficient, with a slight rotation thereof, to force the drill past such obstacles until the bottom of the well is reached.

When the drill is upon the bottom of the 50 hole the drill stem will then be rotated. This rotation communicated to the upper section of the drill stem will rotate the barrel 1 and the nipple 5 to screw said nipple downwardly upon the bushing 11. This will also 55 screw the said nipple off of the head 8 on the drive stem.

When the head 8 has been disconnected in this manner it is free to slide upwardly in the barrel 1, and due to the fact that the coupling 60 5 is screwed down over the bushing 11 the upper portion 13 of the bushing will project upwardly past the threaded seat 7 and prevent the head 8 from again being screwed into the seat 7. With the parts thus disconnected the upper section of the drill stem may

be supported by the derrick and the weight of the lower section will rest upon the drill at the bottom of the hole. The driller will first allow the upper section of the drill stem to drop downwardly over the drive stem 9 until the parts are entirely telescoped together, then by supporting the upper section from the derrick and rotating the drill, the progress of the drill downwardly through the formation will cause it to gradually move downwardly relative to the barrel 1 until it has drilled a sufficient depth to allow the insertion of another section of drill stem at the upper end of the string. When this is done, the parts will be again telescoped together 75 and the operation repeated. 80

It will be seen that by my device a uniform weight will be supported upon the drill at all times so that best results may be obtained. It will be determined by the driller through experiment exactly what weight of drill stem is most effective in the operation of the drill and the joint may be located in the string at the proper point to obtain the weight desired. 85

The advantages of my construction lie in the fact that the parts can not telescope together during the introduction of the drill stem into the hole, due to the manner in which they are connected during the time the drill is being inserted to the bottom. Thus if an obstruction is encountered in the well which might tend to cause the upper and lower sections at each side of the joint to be telescoped together they will be held from so doing by 90 my connection. This will prevent the accidents which are liable to happen from telescopic joints in the drill stem, due to the dropping of the lower section of stem away from the upper one after the obstruction is passed. Furthermore, it will be impossible to make 95 the connection between the head 8 and nipple 5 during the drilling operation, due to the position of the bushing 11 when the parts are disconnected. The further advantages of the 100 device will be obvious to those skilled in the art. 105

What I claim as new is:

1. A slip joint for drill pipe including two sections, one slidably relative to the other, means on one section engageable by means on the other to hold the said sections from relative longitudinal movement releasable on relative rotation, and means to thereafter prevent similar engagement of said sections. 115

2. In a drill pipe, a slip joint including a barrel, a drive stem, a piston head thereon slidable in said barrel, a nipple on said barrel, a bushing engageable in said nipple, and non-rotatably engaging said drive stem. 120

3. In a drill pipe, a slip joint including a barrel, a drive stem, a piston head thereon slidable in said barrel, a nipple on said barrel, a bushing engageable in said nipple and non-rotatably engaging said drive stem, said head 125

being releasably connected with said nipple.

4. In a drill pipe, a slip joint including a barrel, a drive stem, a piston head thereon slidable in said barrel, a nipple on said barrel, 5 a bushing engageable in said nipple and non-rotatably engaging said drive stem, said head being screwed into connection with said nipple and releasable on rotation of said pipe.

10 5. In a drill pipe, a slip joint including a barrel, a drive stem, a piston head thereon slidable in said barrel, a nipple on said barrel, a bushing engageable in said nipple and nonrotatably engaging said drive stem, said head having a threaded connection with said 15 nipple releasable on rotation of said drill pipe relative to said stem, and means to thereafter prevent engagement of said threaded connection.

20 In testimony whereof I hereunto affix my signature this 4th day of March, A. D. 1929.

ROBERT A. LINCOLN.
